(57) **CLAIM**

The ornamental design for the left wheel fairing, as shown and described.

DESCRIPTION

FIG. 1 is of a left wheel fairing shown in an environment of use, in accordance with the present design;

FIG. 2 is a front view of the left wheel fairing shown in FIG. 1, removed from an environment of use for clarity of disclosure;

FIG. 3 is a back view of the left wheel fairing shown in FIG. 2;

FIG. 4 is a top plan view of the left wheel fairing shown in FIG. 2;

FIG. 5 is a bottom plan view of the left wheel fairing shown in FIG. 2;

FIG. 6 is a right side view of the left wheel fairing shown in FIG. 2; and,

FIG. 7 is a left side view of the left wheel fairing shown in FIG. 2.

The broken line showing of an aircraft is for the purpose of illustrating environmental structure and forms no part of the claimed design.
